HEAT EXCHANGER

Richard Henry Pearse, Jr., and Alan George Butt, La Crosse, Wis., assignors to The Trane Company, La Crosse, Wis.

Application December 4, 1953, Serial No. 396,125

2 Claims. (Cl. 257—241)

This invention relates to heat exchangers and particularly to heat exchangers for cooling the oil and heating the fuel of an engine.

The passageway for one of the fluids is formed by a series of flat plates which require the fluid to flow in a tortuous path of great length.

The other fluid is conducted through the heat exchanger by a plurality of separate passageways in the form of tubes so that each tube may receive and discharge a metered quantity of fluid.

A general object of this invention is the provision of a very efficient heat exchanger that is simple to construct, inexpensive to manufacture and strong and durable in use.

Another object of the invention is to provide a heat exchanger which can be made by assembling simple structural elements and brazing or welding them to form an integral structure.

It is another object of this invention to provide a block-off tube inside of each tubular passageway to increase the velocity of flow and to increase the amount of prime surface.

Other objects and advantages of the invention will be clearly apparent as the specification proceeds to describe the invention with reference to the accompanying drawings, in which—

Fig. 1 is a plan view of the heat exchanger of this invention.

Fig. 2 is a side view partly in section to show the interior construction.

Fig. 3 is an end view of the improved heat exchanger.

Fig. 4 is a sectional view taken on line 4—4 of Fig. 1.

Fig. 5 is a sectional view taken on line 5—5 of Fig. 1.

Fig. 6 is a sectional view taken on line 6—6 of Fig. 4.

Fig. 7 is a plan view of a fin of one series.

Fig. 8 is a plan view of a fin of a second series.

Fig. 9 is a fragmentary sectional view of a portion of the fins taken on the line 9—9 of Fig. 7.

Fig. 10 is a diagrammatic view showing a portion of the path of fluid flow through the heat exchanger.

Referring to Figs. 1—3, numerals 10 and 12 designate the tube sheets of the exchanger. A plurality of fins 13 and 14 lie between the tube sheets 10 and 12 and are fastened to each other and to the tube sheets by closure strips 16.

Two manifolds 18 are brazed to the tube sheet 10, and to the fins 13 and 14, and to the closure strips 16 which the manifolds 18 overlie. Two manifolds 20 are similarly brazed to the tube sheet 12 and to the fins 13 and 14 and to the closure strips 16 which the manifolds 20 overlie.

Manifolds 18 and 20 have openings 22 and 24 respectively which are adapted to be connected to fluid supply and discharge conduits respectively. For purposes of description it will be assumed that openings 22 are connected to fluid supply conduits and openings 24 are connected to fluid discharge conduits. It should be understood that the flow may be in the opposite direction if desired.

2

In the space between the tube sheet 10 and the adjacent fin 13 is a corrugated sheet 26 which rests on the tubes 28 and supports closure members 30 and 32. A corrugated sheet 26 is similarly arranged between tube sheet 12 and adjacent fin 13.

It is thus seen that fluid entering through opening 22 in manifold 18 is conducted by manifold 18 to the space between adjacent fin 13 and tube sheet 10. The fluid then flows through hole 34 in fin 13 into the next space from 10 which it flows through circular holes 36 and triangular holes 38 of fin 14. The fluid then flows through the center hole 34 of the next fin 13. As clearly shown in Fig. 10, the fluid continues to flow in this manner throughout the length of the heat exchanger and is discharged through manifolds 20 and the holes 24 therein.

Fins 13 and 14 have holes 40 and 42 respectively which receive tubes 28. Fins 13 have upwardly offset portions 44 and downwardly offset portions 46. The height of portions 44 and 46 is such that they contact and are 20 welded to the next adjacent fins. The offset portions therefore maintain uniform fin spacing, and they contribute to the strength and rigidity of the structure. The offset portions 44 and 46 also function as obstructions to direct the flow into intimate contact with the tubes.

Inside of each tube 28 is corrugated fin 48 and an internal tube 50 closed by a cap 52. In assembling the heat exchanger before brazing, the tubes 28 are assembled in the tube sheets 10 and 12 and in the fins 13 and 14. The tubes 28 are then expanded as by forcing an expanding bullet therethrough, or by subjecting the tubes to fluid pressure.

When expanded, the tubes 28 hold the tube sheets 10 and 12 and the fins 13 and 14 in assembled relationship. The fins 48 are then inserted in the tubes 28 and the inner tube 50 is inserted internally of the fins 48. The tube 50 is then expanded as by forcing an expanding bullet therethrough. After expansion of tube 50, fin 48 is in forced engagement with tubes 28 and 50. After brazing, the fins 48 are brazed to the tubes 28 and 50 and the caps 30 52 are brazed to the tubes 50.

In tube sheets 10 and 12, a groove 53 surrounds each fluid entrance and is adapted to receive an O-ring of neoprene or other flexible material to seal the tubular passageways of the heat exchanger with respect to the supply and discharge conduits, not shown. Threaded holes 54 in tube sheets 10 and 12 are adapted to receive screw members, not shown, which hold the supply and discharge conduits in sealing engagement with the tube sheets 10 and 12 of the heat exchanger. Threaded studs 56 extend from 45 the edges of tube sheets 10 and 12 and are adapted to secure supply and discharge conduits, not shown, in communication with openings 22 and 24 in manifolds 18 and 20.

We prefer to make the elements of this heat exchanger 55 of aluminum. The fins 13, 14, 26 and 48, and the closure members 16, 30 and 32 have on their contacting faces a brazing alloy which melts at a lower temperature than the parent metal. It should be understood that, if desired, only one of two contacting surfaces need have the 60 brazing alloy coating. Brazing rings and brazing foil are also mounted in or adjacent to other joints which are to be brazed. Brazing foil is used between the contacting surfaces of manifolds 18 and 20, and members 10, 12, 16, 30 and 32. The elements are held in assembled arrangement by a fixture. The fixture and assembled elements are immersed in a salt bath containing suitable flux at a temperature of approximately 1100° F. to melt the brazing alloy and cause the elements to be brazed or welded into an integral structure.

70 It should be understood that metals other than aluminum can be used. It is only necessary to subject the assembly to the proper brazing temperature for the metals

used and to carry out the brazing process in the presence of a suitable flux or atmosphere.

While we have described the foregoing preferred embodiments of our invention, we contemplate that many changes may be made without departing from the scope or spirit of our invention, and we desire to be limited only by the claims.

We claim:

1. A heat exchanger comprising spaced substantially flat and parallel tube sheets, a plurality of spaced fins between said tube sheets, said fins lying in planes substantially parallel to said tube sheets, closure means extending along the peripheral edges of the fins to enclose the spaces between the fins, a plurality of tubes extending through said fins and into the openings in said tube sheets, said tubes being adapted to conduct a first heat exchange fluid, closure strips between the tube sheets and the fins adjacent the tube sheets, said closure strips extending along all but a portion of the peripheral edges of said adjacent fins to provide elongated openings, means supported by said tubes, said means engaging and supporting said closure strips at the extremities of said elongated openings, manifolds secured to said tube sheets and having passageways communicating with said elongated openings, said manifolds being adapted to receive and discharge a second heat exchange fluid, said fins having openings therethrough for the passage of said second heat exchange fluid from one tube sheet to the other.

2. A heat exchanger comprising spaced substantially flat tube sheets, a plurality of spaced fins between said tube sheets, said fins lying in planes substantially parallel to said tube sheets, closure means extending along the peripheral edges of the fins to enclose the spaces between the fins and the spaces between the tube sheets and the fins, first tubes extending through said fins and into open-

ings in said tube sheets, said first tubes being brazed to said fins, second tubes inside of said first tubes, corrugated fins in the spaces between the first and second tubes, means brazing said corrugated fins to said first and second tubes, means closing said second tubes to limit movement of a first heat exchange fluid to the spaces between said first and second tubes, a supply manifold secured to one of said tube sheets, said supply manifold being adapted to be connected to a source of a second heat exchange fluid and having a passageway communicating with the space between said one tube sheet and the fin adjacent thereto, a discharge manifold secured to the other of said tube sheets, said discharge manifold having a passageway communicating with the space between the other of said tube sheets and the fin adjacent thereto, said fins having openings therethrough, the openings in alternate fins being offset from the openings in the other fins to cause said second heat exchange fluid to flow in a zigzag path from one tube sheet to the other tube sheet.
